SHOE LAST

Theodore F. Whitmore and Ila R. Rounsville,
Los Angeles, Calif.Application July 5, 1932, Serial No. 620,906
Renewed July 10, 1935

9 Claims. (Cl. 12—123)

This invention is a shoe last adapted for use in repairing worn shoes and fitting new shoes to the individual wearer; and has for its object to provide a structure having supporting surfaces conforming to the various parts of the shoe so as to present a rigid backing for the entire area of whatever part of the shoe is being worked upon.

It is a further object of the invention to arrange the various supporting surfaces for operative assembly within a compact space, and to adapt the assembly for interchanging and reassembling of parts so as to position the desired supporting surface for convenient mounting of a shoe thereon, whereby the desired portion of the shoe is readily accessible to the operator.

It is a further object of the invention to properly arrange the device as a portable structure adapted for ready disassembly of its parts so as to occupy but little space during transportation, and as readily assembled for use with the shoe supporting surfaces mounted on a standard which is supported by a base resting upon the floor and insuring rigid and stationary structure when the device is in use.

It is a still further object of the invention to arrange the different supporting surfaces so as to fit the complementary parts of shoes of various sizes, but to preferably provide certain of the units in two sizes so that the unit of each size is particularly adapted for use in connection with the range of sizes encountered respectively in men's and ladies' shoes.

More particularly it is the object of the invention to provide supporting surfaces adapted for convenient engagement by complementary parts of a shoe without distorting that portion of the shoe which is not being worked upon, and respectively provides a supporting surface for working upon the counter seams and heel of a shoe, a supporting surface for working upon the vamp seams and the sole of a shoe, a surface for working upon the toe cap of a shoe, and a surface for working upon the arch, heel and sole of a flat-heel shoe.

Further objects of the invention will be readily understood from the following description of the accompanying drawing, in which:

Fig. 1 is a front elevation of the invention.

Figs. 2 and 3 are side elevations, looking respectively at opposite sides.

Figs. 4 and 5 are fragmentary front elevations respectively showing different assemblies of the component units.

Fig. 6 is a side elevation of the structure shown in Fig. 5.

Figs. 7 and 8 are transverse sections on the line 7—7 and 8—8 respectively of Fig. 1.

Fig. 9 is a transverse section on the line 9—9 of Fig. 5.

The device is preferably portable and readily disassembled for transporting, but forming a conveniently assembled and rigid structure when in use. For this purpose a base 1, preferably 10 provided with cushioning blocks 2, is adapted to rest upon the floor but may be readily moved from place to place, and a standard 3 is detachably mounted on the base and supports the various shoe engaging surfaces at a height convenient to the operator, who by placing his foot upon the base and resting his weight thereon readily keeps the entire structure stationary on the floor. The base 1 is preferably a circular plate and has an upstanding socket 4 at its 20 axis, adapted to detachably receive a cooperating tongue 5 at the lower end of standard 3. The cooperating tongue and socket preferably are adapted for longitudinal engagement so as to provide a tight wedging engagement whereby 25 the standard is rigidly supported with relation to the base and is held against detachment thereupon until some appreciable force is exerted for withdrawing the tongue from the socket.

A cross-arm is detachably mounted on the upper end of standard 3, and has vertically lined sockets 6 and 7 respectively opening through the upper and lower faces of the cross-arm, and adapted for selective engagement by a tongue 8 35 at the upper end of the standard, whereby the cross-arm may be mounted on the standard, as shown in Fig. 1, or may be reversed as shown in Fig. 3. The cooperating tongue and socket 8—6 or 8—7 preferably taper, but a shoulder 9 at 40 the base of tongue 8 is adapted to engage the mouth of its cooperating socket and the end of the tongue is adapted to engage the closed base 10 of its socket for limiting the wedging engagement between the tongue and socket so as 45 to simply provide a snug fit which will hold the cross-arm rigid with relation to its standard, but without so wedging the tongue in the socket as to necessitate any appreciable force for removing the cross-arm.

It will thus be seen that the cross-arm may be removed from the standard by exerting such little force as will not disturb the tightly wedged tongue and socket engagement 5—4, at the lower end of the standard and which can only 50 55

be disengaged by exerting some appreciable force; and consequently when the device is once operatively assembled, there is no liability of inadvertently disconnecting the base and standard 5 when it is desired to merely interchange and reverse the cross-arms which are mounted on the upper end of the standard.

The cross-arm preferably comprises shanks 11-12 projecting laterally from opposite sides 10 of its socket structure, with the shank 11 terminating in a knob 13 which is used when working upon the counter seams or heel of a shoe, and the shank 12 being downwardly inclined as shown at 14 and terminating in an enlargement 15 which is used when working upon the vamp 15 seams or the sole of a shoe.

The knob 13 is a truncated ellipsoid forming a flat elliptical surface 16 at its outer end as shown in Fig. 2 and against which the heel 20 portion of a shoe is adapted to rest with the counter of the shoe received over the knob 13 as shown in Fig. 1; and the cross-sectional and longitudinal curvatures of the upper and lower 25 portions of the ellipsoid 13 are symmetrical and conform to the curve of the counter of a shoe as shown at 17, so as to provide a complementary backing for the counter when the cross-arm is in either the position shown in Fig. 1 or that shown in Fig. 4. A shoe, irrespective of its size, 30 may thus be readily mounted on the knob 13 with the surface 16 and 17 forming a complementary backing for the heel and the counter of the shoe, thereby providing for conveniently working upon the heel, but more particularly applicable for smoothing out the counter seams 35 of a shoe so as to insure a comfortable fit.

The enlargement 15 at the end of shank 12 preferably projects upwardly at a slight angle from the depending shank-end 14, and is of a shape to snugly fit within the vamp of a shoe. 40 For this purpose the enlargement 15 forms a substantially flat bottom surface 18 tapering to a toe 19 at its forward end as shown in Fig. 3, and rearwardly from the toe, the body of the enlargement gradually tapers to an increasing width and thickness as shown in Figs. 1 and 3, so as to form a tapering curved surface 20. The vamp of a shoe, irrespective of its size, is thus adapted to be drawn over the enlargement 50 15 and wedged thereon, before the toe of the last engages the toe of the shoe, as shown in Fig. 1, with the surface 18 forming a flat complementary backing for the sole of the shoe and the surface 20 conforming to the contour of and forming a complementary backing for the vamp of the shoe. As shown in Figs. 1 and 8 the vamp 55 seams of a shoe may thus be readily smoothed out, using the surface 20 as a backing, and by reversing the cross-arm as shown in Fig. 4, and using the surface 18 as a backing, the sole of the shoe may be worked upon for smoothing out irregularities, limbering the sole, etc; it being noted that during these operations and particularly in the case of ladies' shoes which have a high arch, the angularly disposed shank-end 14 affords ample clearance between the supporting shank and the rear portion of the shoe as shown in Fig. 1, so that the shoe may be readily operatively positioned without distortion.

Means are also provided for breaking down excessive stiffness and raising the toe box of a shoe; and for this purpose whichever of the sockets 6-7 of the cross-arm is not engaged by tongue 8, is adapted to detachably receive a cooperating tongue 22 of a shank 23 which is

preferably angularly offset as shown at 24 and which terminates in an enlargement 25. The enlargement 25 is adapted for reception in the toe box of a shoe as shown in Fig. 3, with the angular offset 24 readily permitting such assembly with ample clearance between the rear portion of the shoe and the supporting shank 23; and the enlargement 25 has a tapering and rounded end 26, and in rear of its rounded end is, in cross-sections, an elongated rectangle having its corners rounded off as shown at 21. The rounded end 26 is adapted to stretch the toe box of a shoe by forcing the shoe downwardly over the enlargement 25, and by then twisting the shoe from side to side on the enlargement 25 as will be understood by reference to Fig. 7, the diagonally opposite pairs of rounded corners 27 wedge in the toe box alternately along the lines A-A and B-B, so as to distort and thereby soften and stretch the toe box. Fig. 7 shows the shoe twisted in that direction for stretching the toe box along the diagonal A-A.

The invention also provides a supporting surface for flat heel shoes such as men's shoes and ladies' sport shoes, with said supporting surface conforming to the arch of the shoe and thereby fitting snugly against the entire length of the shoe, so that without distorting the shoe either its sole, heel or arch may be worked upon against the complementary backing which is formed by the supporting surface, thus particularly providing means whereby the stiffness such as are now usually provided in the arches of flat-heel shoes may be restored to their original contour in the event that their curvature has been broken down.

As an instance of this arrangement a shank 30 is provided with a tongue 31 which is adapted for reception in the upwardly opening socket 6 or 7 of the previously described cross-arm structure; it being understood that the shanks 23 and 30 are interchangeably employed, and that whichever element it is desired to use is detachably mounted on the cross-arm as shown in Figs. 1 and 5 respectively. The tongue 31 tapers to conform to sockets 6-7; and as previously described in connection with the tongue and socket engagements 8-6 and 8-7, the tongues 22 and 31 are preferably shouldered at their bases as shown in 40 32 and 33 respectively, and are adapted to seat at said shoulders and against the base 10 of their cooperating socket, so as to limit their reception in their cooperating socket to simply a snug fit and not a tight wedging engagement, whereby 50 either the shank 22 or 30 is held rigidly in place, but may be readily removed without exerting such appreciable force as would be liable to accidentally disengage the tight wedging engagement at the tongue and socket 5-4 which is provided between base 1 and standard 3.

The shank 30 supports a laterally projecting abutment element 35 over which a flat-heel shoe is adapted to be received with the abutment element forming a complementary backing for the 65 sole, shank and heel of the shoe. For this purpose the working surface of the abutment element conforms in plan view to the outline of the sole, shank and heel; and below said working surface the abutment element is curved in both longitudinal and cross-section so as to merge into the supporting shank 30 as shown in Figs. 5 and 6, with a definite vertical web 36, extending 70 longitudinally of the forward portion of the 75

abutment element for strengthening the entire structure as shown in Fig. 9.

The sole portion 37 of the working surface of the abutment element 35 curves downwardly at its rear end and merges into the shank portion 38 of the working surface, and the shank portion 38 curves upwardly at its rear end and merges into a slightly curved heel portion 39, but the general direction of each of the slightly curved surfaces 37, 38, and 39, is substantially horizontal, whereby both the sole portion 37 and the heel portion 39 are higher than the shank portion 38, and the sole portion 37 is higher than the heel portion 39, thereby conforming the entire working surface to the natural contour of the bottom of a shoe as shown in Fig. 5, so as to form a complementary backing for working upon any part of the bottom of a shoe, irrespective of the size of the shoe, and particularly providing a shank depression between the heel and sole so that the shank of the shoe may be worked down into said depression for restoring its normal arched contour.

It will be apparent that all of the various supporting surfaces for the different parts of a shoe are adapted to form complementary backings for shoes of different size, for example the curvature and taper of the elements 13 and 15 is such that shoes of different size will snugly fit the same by being drawn a greater or less distance over said elements, but in practice it may be desired to furnish elements such as 13, 15, and 35 in a plurality of sizes, particularly adapted for men's and ladies' shoes respectively. As an instance of this arrangement the cross-arm shown in Figs. 1 and 4 has elements 13 and 15 of a size particularly adapted for ladies' shoes while Fig. 5 shows a similar and interchangeable cross-arm having elements 13a and 15a of a larger size particularly adapted for men's shoes. The abutment element 35 which is shown in Figs. 5 and 6 is also of a size particularly adapted for men's shoes, and a similar element (not shown) of smaller size for ladies' shoes may be supplied for interchangeable use in connection with the cross-arm shown in Figs. 1 and 3.

The invention thus provides a simple and inexpensive device, which within a compact space and by various assemblies of interchangeable units provides a complementary backing snugly fitting the contour of any desired part of a shoe, with the various elements readily assembled, interchanged, replaced and disassembled, and when operatively assembled providing a strong and rigid structure, particularly as a result of the reception of tongues 22 and 31 in sockets 6 or 7 whereby the tongues form with their shanks an extremely strong structure avoiding any possibility of breakage at the junction of the tongues with their shanks. It will also be noted that the tongues 5, 8, 22, and 31 are cross-sectionally appreciably elongated so that their width is in the plane of the lateral projection of shanks 11-12, so that strain on the assembled structure when using any of its various supporting surfaces, is opposed by the appreciable width of the tongues, in order to insure an extremely sturdy assembly.

We claim:

1. In combination, a base, a standard adapted for detachable mounting on the base by means of cooperating tapering tongue and groove elements arranged for such engagement of said tapering elements as to insure a relatively tight wedging mounting, and a shoe last adapted for

detachable mounting on the standard, said last mentioned detachable mounting comprising a cooperating tapering tongue and groove adapted for snug wedging engagement but having means for limiting their relative movement to engaging position so as to restrict the wedging engagement whereby said last mentioned detachable mounting is adapted for ready disengagement by exerting such little strain thereon as will not disengage the first mentioned tight wedging mounting. 10

2. In combination, a standard terminating in a tongue, a transverse member having sockets in its upper and lower faces, one of said sockets being adapted to receive the tongue for mounting the transverse member on the standard, the 15 transverse member having a supporting surface conforming to a part of a shoe, and a member having a tongue adapted for reception in the other socket, said member having a supporting surface conforming to a different part of a shoe. 20

3. A shoe last comprising a tapering enlargement adapted for reception in a shoe and having opposite surfaces, one of which conforms to the vamp portion of the shoe and the other of which forms a solid backing for the sole of the shoe, the 25 larger end of the tapering enlargement being of a dimension between said opposite surfaces and in comparison with the length of the last whereby said enlargement fits snugly and wedges in the vamp of the shoe before the end of the last 30 engages the toe of the shoe.

4. In combination, a transverse shank, an enlargement at one end of the shank comprising a truncated ellipsoid forming a flat elliptical surface at its outer end, an offset at the opposite 35 end of the shank terminating in a tapering enlargement adapted to fit snugly within the vamp of a shoe and having a flat bottom surface adapted to engage the sole of the shoe, and means for selectively mounting the transverse 40 shank with said flat bottom surface turned upwardly or downwardly, the truncated ellipsoid providing a curved surface at its upper side irrespective of said selective mounting of the transverse shank. 45

5. In combination, a standard, and a shoe last having means for detachably mounting it relative to the standard and comprising an enlargement substantially rectangular in cross-section with its corners rounded off and tapering at its 50 end for reception in the toe of a shoe, whereby twisting the shoe on the enlargement is adapted to exert pressure against the toe box.

6. In combination, a standard, and a shoe last having means for detachably mounting it relative to the standard and comprising a vertically disposed shank having an offset end terminating in a vertically disposed elongated enlargement substantially rectangular in cross-section with its corners rounded off and tapering at its end for 60 reception in the toe of a shoe, whereby twisting the shoe on the enlargement is adapted to exert pressure against the toe box, with the rear portion of the shoe positioned clear of the shank 65 as a result of the offset therein.

7. In combination, a standard, a transverse shank, an enlargement at one end of the shank comprising a truncated ellipsoid forming a flat elliptical surface at its outer end, an enlargement 70 at the opposite end of the shank having opposite surfaces respectively conforming to different parts of a shoe, and means for selectively mounting the transverse shank on the standard with either of said opposite surfaces turned upwardly. 75

the truncated ellipsoid providing a curved surface at its upper side irrespective of said selective mounting of the transverse shank.

8. In combination, a standard terminating in a tongue, a transverse member having sockets in its upper and lower faces, the transverse member being adapted for insertion in a shoe and having vertically opposite surfaces respectively conforming to the sole and vamp portions of the shoe, the sockets being adapted to selectively receive the tongue for mounting the transverse member on the standard so that either the sole or vamp surface of the transverse member is uppermost.

9. In combination, a standard, a transverse

shank on the standard, an enlargement at one end of the shank forming a flat surface at its outer end and having a curved surface extending from the flat surface along the length of the enlargement, whereby the rear portion of a shoe is adapted for reception on the enlargement with the heel of the shoe against the flat end surface and the counter of the shoe received against the curved surface of the enlargement, and an enlargement at the opposite end of the shank adapted for reception within the vamp portion of a shoe.
